H. C. ANDERSON

PAPER CONTAINER OR RECEPTACLE

Filed March 22, 1923

INVENTOR
Harry C. Anderson,

BY
C. P. Goepel

ATTORNEY

UNITED STATES PATENT OFFICE.

HARRY C. ANDERSON, OF YONKERS, NEW YORK.

PAPER CONTAINER OR RECEPTACLE.

Application filed March 22, 1923. Serial No. 626,735.

To all whom it may concern:

Be it known that I, HARRY C. ANDERSON, a citizen of the United States, and a resident of Yonkers, county of Westchester, and State of New York, have invented certain new and useful Improvements in Paper Containers or Receptacles, of which the following is a specification.

This invention relates to paper containers or receptacles, and more particularly to a container for tea leaves or the like, designed for individual use in the preparation of a beverage.

It is the primary object and purpose of my present improvements to provide a paper container for the above purpose having foraminated walls which may be served in restaurants to individual patrons so that when immersed in hot water contained in the cup, the water will pass freely through the foraminous walls of the container into contact with the tea leaves therein whereby a fusion may be produced from said tea leaves of a strength satisfactory to the taste of the individual.

It is another important object of the invention to provide a paper tea container which may be readily produced by machine at small cost, and which is securely sealed so as to prevent the release of the tea leaves into the cup upon the softening of the paper by the action of heat and moisture.

In one practical embodiment of the invention, I provide a container of the above character of elongated pyramidal or cylindrical form, the walls of which are perforated for a portion of the length of the container, the remaining portions of the container walls being imperforate so that part of the container can be grasped between the fingers of the hand to immerse or remove the container from the water without wetting the fingers.

With the above and other objects in view, the invention consists in the improved container or receptacle, and in the several structural features thereof as will be hereinafter more fully described, illustrated in the accompanying drawing and subsequently incorporated in the subjoined claims.

In the drawing wherein I have shown several simple and practical embodiments of the invention and in which similar refer-

ence characters designate corresponding parts throughout the several views: 55

Figure 1 is a perspective view illustrating the manner of use of the device;

Figure 2 is a side elevation showing one form of the invention;

Figure 3 is a similar view, the container 60 being partly broken away and turned at an angle of 45° from the position shown at Figure 2;

Figure 4 is an end elevation;

Figure 5 is a transverse section taken on 65 the line 5-5 of Figure 3;

Figure 6 is a side elevation illustrating a modified construction of the device;

Figure 7 is a similar view looking at right angles to Figure 6 and with a part of the 70 container wall broken away;

Figure 8 is an end elevation of the modified form of the device; and

Figures 9, 10 and 11 are views corresponding to Figures 6, 7 and 8 illustrating another 75 alternative construction.

Referring in detail to the drawing and more particularly to Figures 1 to 5 thereof, the container is formed from a single sheet of paper of suitable size and shape. This 80 paper sheet is wound upon a mandrel of predetermined form to provide the overlapping convolutions 5. If desired, the overlapping portions may be adhesively secured to each other. As seen in Figures 2 and 3, 85 of this embodiment of the invention, the container or receptacle is in the form of an elongated pyramid, the point or apex 6 of which is securely sealed in any preferred manner.

The paper sheet from which the container is formed is provided with closure flaps 7 which extend from the opposed walls of the pyramidal body of the container at the base thereof and are adapted to be folded inwardly into superposed relation upon each other after the container has been filled with tea leaves, whereby the base end of the container is closed. The outermost superposed closure flaps 7 are permanently connected 100 to each other by means of a suitable fastener indicated at 8.

Preferably, the lower and intermediate portions only of the container are of rectangular form in cross-section, the upper relatively small end portion thereof being of

circular cross-sectional form as shown at 9 so that this end of the container may be conveniently grasped between the fingers of the hand. After the container has been 5 formed as above described, it is placed in a suitable mold, and the lower and intermediate portions of its walls are perforated as at 10, said perforations being of very small diameter so that the tea leaves may 10 not pass therethrough. The water may, however, readily enter to the interior of the container so that the tea leaves will become fairly steeped in a relatively short time. The paper from which the container 15 is formed is of a special grade, no chemicals being used in the manufacture thereof so that a disagreeable taste will not be imparted to the tea by the action of the heat and water upon the paper walls of the container. I have used a good commercial 20 grade of vegetable parchment paper and have found that the same not only withstands the action of boiling water without disintegration but when wet, is considerably 25 toughened so that the paper is capable of withstanding high tensile strains.

A container or receptacle for individual use of the character above described may be produced at such small cost, that it can be 30 furnished by restaurant proprietors to patrons, the container being used but a single time, and then destroyed. Thus the user may concoct a beverage to suit his own individual taste, the strength thereof depending upon 35 the length of time the container with its contents remains immersed in the hot water.

In Figures 6, 7 and 8 of the drawing I have illustrated a slightly modified form of the invention in which the container 11 is of 40 cylindrical form. In this instance likewise, the container is formed on a mandrel from a single sheet of paper, one end 12 thereof being permanently sealed, and the other end having the closure flaps 7'. The cylindrical 45 wall of the container for a portion of its length is perforated as at 10'. It will be understood that in each case, the container is not completely filled with tea leaves, but these leaves represented at T fill the container 50 only for a depth equal to the extent of the perforated portion of the container wall. Thus the tea leaves may freely expand within the container without bursting the latter.

55 In Figures 9, 10 and 11 there is shown another alternative embodiment of the device in which the paper container has a cylindrical portion 13 extending from the permanently sealed end 14 thereof, such 60 cylindrical portion of the container being perforated as at 15. The remaining portion of the container is of gradually decreasing diameter and the opposite end is flattened as at 16, the side walls thereof being brought 65 closely together and the ends of said walls

folded over as at 17 and securely fastened by means of the wire or other suitable fastening element 18. I have stated that my device may be used with advantage by restaurants and the like, but of course, it is 70 evident that it lends itself also and specifically to use in the home because of the definite portion, convenience and sanitary condition.

It will be seen that any one of the three embodiments of the device above described 75 may be rapidly produced by merely winding the paper sheeting upon a suitably formed mandrel. The imperforate section of the container permits the same to be securely 80 grasped and immersed in the water or removed therefrom without staining or wetting the fingers. In addition to the above 85 constructions which I have herein specifically referred to, it is possible that the same advantageous results might be obtained in 90 other modified forms of the invention. Accordingly, it is to be understood that no limitations are to be implied from the foregoing reference to structural details and that I reserve the privilege of adopting all such legitimate 95 modifications thereof as may be fairly embodied within the spirit and scope of the invention as claimed.

I claim:

1. A container composed of a sheet of material having overlapping relatively fixed spiral convolutions providing a container body of elongated form, said container being permanently sealed at one of its ends and having a foraminous wall section, the sheet 100 having flaps projecting from the opposite end of the container body in opposed relation to each other and adapted to be folded inwardly to close the latter end of the container, and fastening means for said closure 105 flaps.

2. A container composed of a sheet of material having overlapping relatively fixed spiral convolutions providing a container body of elongated form, said container being 110 permanently sealed at one of its ends, the sheet having flaps projecting from the opposite end of the container body in opposed relation to each other and adapted to be folded inwardly to close the latter end of the container, and fastening means for said closure 115 flaps, the walls of said container being provided with closely adjacent perforations extending from one end of the container to a point spaced from the opposite 120 end thereof.

3. A container formed from a single sheet of paper spirally wound to provide overlapping convolutions and forming an elongated container body, means permanently 125 closing the container at its opposite ends, the body wall of the container being provided with closely adjacent perforations extending from one end thereof to a point substantially midway of its length. 130

4. A container formed from a single sheet of paper having spirally wound overlapping convolutions providing an elongated container body having a major portion of pyramidal shape, said pyramidal shaped portion of the container body gradually merging into a conical apex portion, means permanently closing the container at its opposite ends, and the walls of the pyramidal shaped portion of the container body being provided with closely arranged perforations. 10

In testimony that I claim the foregoing as my invention, I have signed my name hereunder.

HARRY C. ANDERSON.
